7 Claims. (Cl. 66—84)

1

This invention concerns means by which an elastic rubber weft thread can be laid and knitted into one and the same article in a warp knitting machine having two movable needle bars (Raschel machine) while temporarily more or less extended (i. e. stretched to a greater or less extent).

The invention is illustrated by way of example in the accompanying drawings, in which:

Figures 1a to 1c show the positions of a warp knitting machine thread guide during the laying of the elastic weft thread.

Figures 2a and 2b are longitudinal sections through a holder device for the weft thread in two different positions, on an enlarged scale,

Figure 2c is a plan view of the holder device.

Figures 3a and 3b show an elevation of an electric control mechanism for the holder device (the individual parts being in two different positions).

Referring to the drawings, the holder device (Figs. 2a, 2b, 2c) consists essentially of a small thread guide tube F on a frame HG, which is fastened to the thread guide rail Sch of the warp knitting machine; of a slide Hs; an electric magnet EM and an armature Ei, H₁ and H₂. The entire holder device is marked Hv and operates as follows:

Coming from a bobbin, the endless covered rubber weft thread GS (Figures 1a to 1c) runs in its normal, unstretched condition to the holder device Hv, passes through the thread guide F of the holder Hv which, is moved forwards and backwards lengthwise of the needle bars from the point x to the point z (Figures 1a to 1c) and vice versa, from the point z to the point x. During the motion of the holder device Hv from x to y in the one direction, or from z to y in the other direction, the elastic rubber weft thread is allowed to slide through the holder device freely in an unextended condition (Figure 2a). At the point y, the rubber thread GS is suddenly gripped by the holder device Hv (Figure 2b) in the manner hereinafter described and held fast, so that as the movement of the holder device Hv continues from the point y to the point z, or from the point y to the point x, the rubber weft thread GS is stretched to a larger or smaller extent, being held in position in such extended condition until after the weft thread has been secured in place between the warp-knitting courses, when the to and fro motion of the holder device starts anew. The degree of extension of the rubber weft thread depends upon the distance of the point y from the starting point of the movement

2

of the holder device Hv, i. e. during motion from left to right from the point x and during motion from right to left from the point z, e. g. in Figure 1a the holder device Hv with the thread guide

5 F is moved from the point x past the point y to the point z (from left to right), stretching the rubber thread to a considerable extent, whereas e. g. in Figure 1b the motion is from the point z past the point y to x (from right to left), leaving the rubber weft thread less extended than in Figure 1a. Finally, in Figure 1c, the motion for instance is again from the point x past y to z (from left to right), so that the rubber weft thread remains almost in its normal condition.

10 15 The varying distances from the point y to the point x on the one hand, or from the point z on the other hand, as well as the gripping and releasing of the rubber thread in the holder device Hv, are controlled automatically and positively during the manufacture of the articles on the warp knitting machines, and it is thereby possible to fashion the article being knitted by the alternately reduced or increased extension of the rubber weft thread.

20 25 The holder device Hv with thread guide F serves not only to stretch the elastic rubber thread but to guide and lay it for insertion between the courses. The mode of operation of the holder device Hv, which is controlled electrically, is as follows:

25 At the moment the holder device Hv is set in motion by the thread guide rail Sch to travel from the point x or z, the direct electric current feeding the twin-pole electromagnet EM is interrupted, so that the latter is instantaneously de-energised. At this moment, a spring Fe in tension displaces to the right the slide Hs, which is located in a guide groove, until a stop plate An on the slide Hs strikes against a fixed abutment plate D₂ which extends over the support rail. During this displacement of the slide Hs, a nose N thereon, which engages the part H₂ of the armature, withdraws the armature pole Ei a short distance from the magnet poles, the said armature pole being fixed to the parts H₁, H₂ of the armature, the former of which comprises two lever arms pivoted on the frame HG, whereby the hole L₂ in the slide Hs comes into position between a hole L₁ in the top plate D₁ and a hole L₃ in the main frame HG, so that these three holes coincide with one another, thereby forming, together with the tubular thread guide F fixed to the main frame HG, a straight smooth canal through which the elastic rubber thread

55 GS may slide freely from the starting point x or

z in a normal, unstretched condition while the holder device H_v is in motion.

The moment, however, that the holder device H_v , during its to and fro motion, reaches the point *y*, the electric circuit is closed again through the control mechanism (Figures 3a and 3b.) By this action, the armature of the electromagnet is attracted, thereby displacing the slide H_s to the left whereby the two edges of the hole L_2 in the slide H_s press the rubber weft thread against the lower edge of the hole L_1 in the top plate D_1 and against the upper edge of the hole L_3 in the main frame HG and clamp it fast. During the remainder of the movement of the holder device H_v from the point *y* to the point *z* or from *y* to *x* (Figures 1a, 1b, 1c), the rubber weft thread GS led by the thread guide F will be stretched more or less, depending upon the position of the point *y*), while at the end points (*x* or *z*) it will be held in position for a sufficient period to allow it to be incorporated in the fabric whereupon the motion of the holder device H_v starts anew. The driving of the control mechanism (Figure 3) and the method of operation thereof are as follows:

From the main shaft H_w of the warp knitting machine, a cam Ex_1 is driven by means of a connecting rod Z_5 , a pawl K_1 and a ratchet wheel K_r , a worm S and a worm wheel S_r (change wheel), the said cam, through levers H_1 , H_2 and connecting rods St_1 , St_2 , causing two switch devices SA_1 , SA_2 to be moved slowly upon a slide bar G_{s1} , either towards or away from one another, whereby the point *y* in Figures 1a to 1c is shifted. Each switch device SA_1 , SA_2 comprises a bar T which is slideable on the bar G_{s1} and has a contact button Ko_2 fixed on the outer end thereof, and a contact bar K_s , slideable lengthwise of the bar T and provided with a contact button Ko_1 for cooperation with the button Ko_2 . During each revolution of the main shaft H_w of the warp knitting machine, the ratchet wheel K_r is moved on only exactly by one tooth, so that with the aid of the exchangeable worm wheel S_r the time of rotation of the cam Ex_1 is adjusted exactly to the shape of the article being manufactured.

Directly above the two switch devices SA_1 , SA_2 , on another slide bar G_{s2} , a slide block G_1 with two switch plates S_b is moved to and fro through a certain distance C — D , the said plates being adapted to engage on either side of the respective contact bars K_s and to grip them frictionally during the to and fro motion of the block G_1 . Since the to and fro motion of the switch plates S_b has to coincide with the motion of the thread guide rail Sch with the attached holder device H_v operated by the lever H_3 and the cam Ex_1 driven by the main shaft of the knitting machine, the slide block G_1 is moved by the same lever H_3 that controls the motion of the thread guide rail Sch_1 , through a lever H_4 , connecting rods St_3 , St_4 and slide block G_1 . During the to and fro motion of the switch plates S_b the following action takes place:

For example, during the motion of the slide block G_1 from C to D , after travelling through a part of the distance between C and D , the switch plates S_b frictionally engage the contact bar K_s of the switch device SA_2 , thereby displacing this contact bar a short distance to the right so as to cause the contact button Ko_1 of the said contact bar to touch the contact button Ko_2 on the switch device SA_2 . Instantaneously, an electric circuit is closed through the winding of the magnet EM , the holder device being at the point *y*.

in Figures 1a and 1c, and the rubber thread is clamped fast by the holder device H_v (see Figure 2b). As the slide block G_1 continues to move through the remaining part of the distance from C to D , the switch plates S_b slide on the contact bar K_s for a shorter or longer period, depending on the position of the switch device SA_2 , until the slide block reaches the point D . After the button Ko_1 has come into contact with the button Ko_2 , the electric circuit through the winding of the magnet EM remains closed until the slide block G_1 commences its return movement from D to C . At the beginning of this return movement, the switch plates S_b push the contact bar K_s of the switch device SA_2 back to its initial position, thereby moving the contact button Ko_1 away from the contact button Ko_2 . By the separation of the contact buttons Ko_1 and Ko_2 , the electric circuit through the winding of the magnet EM is interrupted, causing the holder device H_v immediately to release the clamped rubber thread (Figure 2a).

During the further travel of the slide block G_1 from D to C , the switch plates S_b slide along and off the contact bar K_s of the switch device SA_2 and then engage the contact bar K_s of the switch device SA_1 , moving it to the left until the contact button Ko_1 of the said contact bar touches the contact button Ko_2 of the switch device SA_1 , thereby closing the circuit through the winding of the magnet EM and causing the rubber thread to be clamped by the holder device H_v at the point *y* in Figure 1b. The switch plates S_b then slide along the contact bar K_s of the switch device SA_1 while the slide block G_1 moves to the point C , the magnet winding remaining energised and the rubber thread being clamped by the holder device H_v until the switch plates S_b move the contact bar K_s back to its initial position during the initial movement of the slide block G_1 from C to D and interrupt the circuit through the magnet winding by separating the contact buttons Ko_1 and Ko_2 of the switch device SA_1 . As the slide bar G_1 moves further towards D , the switch plates S_b slide along and off the contact bar K_s of the switch device SA_1 to engage again the contact bar K_s of the switch device SA_2 , whereupon the cycle of operations is repeated.

In Figure 3a, the two switch devices SA_1 , SA_2 are separated wide apart by the cam Ex_1 , so that the switch plates S_b , during their to and fro motion through the distance C to D , engage the contact bars K_s after travelling some distance, thereby causing the buttons Ko_1 , Ko_2 to come into contact, rather late. Thus the gripping of the rubber thread in the holder device H_v (viz. the point *y* in Figure 1c) takes place rather late.

Figure 3b shows the two switch devices SA_1 , SA_2 displaced very close to one another by the cam Ex_1 , so that the switch plates S_b during their to and fro motion through the distance C to D will cause the circuit to be closed through the contact buttons Ko_1 , Ko_2 sooner. Thus, the gripping of the rubber thread by the holder device H_v (viz. the point *y* in Figure 1a) takes place sooner.

The movement apart and towards one another of the switch devices SA_1 , SA_2 is a slow process, corresponding to the curve of the cam Ex_1 , whereby the displacement of the point *y* (Figures 1a to 1c) is a gradual one and so is the change in the clamping point *y* of the rubber thread in the holder device H_v .

In the manufacture on warp knitting machines

of the articles hereinbefore mentioned, a plurality of holder devices H_v operate simultaneously, all of which may be fixed to one thread guide rail by means of which they are moved through a certain distance $x-z$, or they may be subdivided and fixed to separate thread guide rails, one of which moves the holder devices H_v to and fro over a longer section, and the other over a shorter section x to z simultaneously, each holder device being adapted, at the right moment and at the right time, to grip and subsequently release an elastic rubber weft thread. The holder device H_v (Figure 2) described, together with the control mechanism therefor (Figure 3) is therefore of great advantage, since by using an electric current and simply switching it on and off, the holder devices can be brought into action to serve the same purpose simultaneously with perfect accuracy and exactly at the moment desired, regardless of the length of the distance x to z to be covered by the holder devices or the time when the mutual to and fro motion of all the holder devices sets in.

We claim:

1. In a warp knitting machine having a driving shaft and two movable needle bars arranged for operation by said driving shaft, means for inserting an elastic weft thread under variable tension in the courses of a fabric during the knitting thereof on the machine, and comprising in combination, a thread guide arranged for reciprocation lengthwise of said needle bars and having driving means connected to said driving shaft for effecting said reciprocation, a gripping device arranged to co-operate with said thread guide for holding and arresting the weft thread, actuating means for said gripping device, and control means arranged for operation by said driving shaft of the knitting machine and adapted to co-operate with said actuating means for actuating the gripping device to hold and arrest the elastic weft thread at an intermediate point in the travel of the thread guide and subsequently release the thread guide after it has been incorporated in the knitted fabric, said control means having adjusting means for varying the point in the travel of the thread guide at which the said actuating means operates the gripping device to arrest the weft thread.

2. In a warp knitting machine, means for inserting an elastic weft thread in the courses of a fabric during the knitting thereof on the machine, comprising the combination as set forth in claim 1, in which the actuating means for the gripping device comprise spring means connected to the gripping device so as to urge the gripping device into its inoperative position to release the weft thread, an electromagnet having an energising winding and an armature in driving relationship with the gripping device and arranged to move the gripping device into its operative position to arrest the weft thread on the magnet winding being energised, and said control means includes switching means arranged to connect said winding to a source of electric current to energise the winding.

3. In a warp knitting machine, means for inserting an elastic weft thread in the courses of a fabric during the knitting thereof on the machine, comprising the combination as set forth in claim 1, in which the thread guide comprises a guide tube through which the elastic weft thread is freely slidable and the gripping device comprises a slide having an aperture therein adapted to allow the elastic weft thread to pass freely

through it, said slide being arranged for reciprocation from an inoperative position in which said aperture is in register with said guide tube into an operative position in which said aperture is out of register with the guide tube so as to clamp the thread between the wall of the aperture and the side of the guide tube.

4. In a warp knitting machine having a driving shaft and two movable needle bars arranged for operation by said driving shaft, means for inserting an elastic weft thread under variable tension in the courses of a fabric during the knitting thereof on the machine, and comprising in combination, a thread guide arranged for reciprocation lengthwise of said needle bars and having driving means connected to said driving shaft for effecting said reciprocation, a gripping device arranged to co-operate with said thread guide for holding and arresting the weft thread, spring means connected to said gripping device to urge the same into its inoperative position to allow the weft thread to pass freely through the thread guide, an electromagnet having an energizing winding and an armature arranged in driving relationship with the gripping device for moving the gripping device into its operative position for arresting the weft thread, on the magnet winding being energized, a pair of switch devices arranged for displacement in a line towards and away from one another, each of said switch devices having a fixed contact thereon and a movable contact bar slidable thereon in the direction of displacement of the switch devices, a switch contact on each contact bar arranged to co-operate with the fixed contact of the respective switch device for connecting the magnet winding to a source of electric current, adjusting means connected to said switch devices and including instrumentalities connected to the driving shaft of the machine for effecting a step-by-step displacement of the switch devices during the successive to and fro movements of the thread guide, so as to vary the distance between the switch devices, an actuating member for said contact bars arranged for reciprocation by said driving shaft and adapted to engage and displace the contact bar of one switch device during a portion of the travel of the actuating member in one direction to bring the switch contact on said bar into operative relationship with the co-operating fixed switch contact, and to engage and displace the contact bar of the other switch device during a portion of the travel of the actuating member in the opposite direction to bring the switch contact of said bar into operative relationship with the co-operating fixed contact.
5. In a warp knitting machine, means for inserting an elastic weft thread in the courses of a fabric during the knitting thereof on the machine, comprising the combination as set forth in claim 4, in which the actuating member for the contact bars comprises a pair of switch plates arranged to engage the contact bars frictionally for moving the switch contacts thereon into operative relationship with the fixed contacts of the respective switch devices, and adapted subsequently to slide relatively to the contact bars.
6. In a warp knitting machine, means for inserting an elastic weft thread in the courses of a fabric during the knitting thereof on the machine, comprising the combination as set forth in claim 1, in which the actuating means for the gripping device include an electro-magnet having an energizing winding and an armature in driving connection with the gripping device for

actuating it to arrest the weft thread, and the control means for said actuating means comprise a pair of switch devices for connecting the magnet winding to a source of electric current arranged for displacement towards and away from each other to vary the distance between them, each of said switch devices having a movable switch member and a switch-actuating member arranged for reciprocation by the driving shaft of the knitting machine so as to be capable of actuating said movable switch members alternately after travelling through a predetermined distance on either side of its mean position, and in which the adjusting means for varying the point in the travel of the thread guide at which the weft thread is arrested include lever mechanism connected to said switch devices for varying the distance apart thereof.

7. In a warp knitting machine, means for inserting an elastic weft thread in the courses of a fabric during the knitting thereof on the machine, comprising the combination as set forth in claim 1, in which the actuating means for the gripping device include an electromagnet having an energizing winding and an armature in driving connection with the gripping device for actuating it to arrest the weft thread, and the control means for said actuating means comprise a pair of switch devices for connecting the magnet winding to a source of electric current arranged for displacement towards and away from one another to vary the distance between them, each of said switch devices having a movable

switch member, and a switch-actuating member arranged for reciprocation by the driving shaft of the knitting machine so as to be capable of actuating said movable switch members alternately after travelling through a predetermined distance on either side of its mean position, and in which the adjusting means for varying the point in the travel of the thread guide at which the weft thread is arrested include a fashioning cam, actuating means connected to said cam and to the driving shaft of the machine for effecting a step-by-step rotation of the cam during the successive to and fro movements of the thread guide, a lever member arranged to co-operate with said fashioning cam, and lever arms connected to said lever member and to the switch devices, and arranged to displace the switch devices simultaneously in opposite directions in accordance with the movements of the lever member cooperating with the fashioning cam.
